Primary Examiner — George D. Kirschbaum*Assistant Examiner* — Lillian Windham(74) *Attorney, Agent, or Firm* — POLSINELLI PC(57) **CLAIM**

I claim the ornamental design for a scale apparatus, as shown and described.

DESCRIPTION

FIG. 1 is a top, isometric view of an embodiment of a scale apparatus, showing my new design;

FIG. 2 is a rear, isometric view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines depict portions of the scale apparatus which form no part of the claimed design.
